CHUCK-KEY HOLDER AND SAFETY DEVICE
FOR POWER TOOLS

Lawrence C. Griffin, Akron, Ohio

Application October 25, 1951, Serial No. 253,115

5 Claims. (Cl. 200—52)

1

This invention relates to improvements in power tools having key-operated chucks.

Heretofore, in the use of such power tools the usual turning keys for adjusting the tool chucks have frequently become misplaced or lost, thereby resulting in costly loss of time on the part of the operators of the tools, as well as the expense of replacing the keys. Moreover, such keys frequently caused injury to the hands of the operators, by being inadvertently retained in the chucks to revolve therewith after the power tools started to operate.

One object of the present invention is to provide a power tool of the type described wherein is incorporated improved means by which the tool cannot be operated unless the adjusting key is stored in a convenient and safe place, whereby is obviated the usual difficulties described above.

Other objects of the invention will be manifest from the following brief description and the accompanying drawings.

Of the accompanying drawings:

Figure 1 is a side elevation of a power hand drill embodying the features of the invention.

Figure 2 is a plan view of the chuck-key holder and safety device of the invention.

Figure 3 is a cross-section taken substantially on the line 3—3 of Figure 1.

Figures 4 and 5 are vertical cross-sections, taken substantially on the lines 4—4 and 5—5, respectively, of Figure 2.

Figure 6 is a wiring diagram illustrating the electrical connections between the drill motor and the safety device.

Referring to Figure 1 of the drawings the numeral 10 designates an electric hand drill of known type having the usual rotary chuck 11 for gripping a drill 12 or other cutting bit, the chuck having in the face thereof a socket 13 for reception of a reduced extension 14 on the shank 15 of a chuck key 16 (see Figures 2 and 4), as shown in chain-dotted lines, in which position a bevel gear 17 fixed on said shank meshes with a bevel gear 18 on a relatively rotatable part 19 of the chuck. A cylindrical pin or cross-arm 20 secured through the outer end of the shank provides freely extending handle portions 21, 21 by which the key is manually turned to rotate the chuck part 19 with respect to chuck part 22, and thereby to tighten or loosen the grip on drill 12. The motor M (see Figure 6) may be connected to a suitable source of electric current by a cable 23.

In order to prevent operation of the hand drill while the key 16 is retained on the chuck 11, a safety key-holder unit 24 is attached to cable 23

5 at a point remote from the hand drill, and in particular from the rotary parts thereof. Unit 24 may comprise a segmental casing formed of dielectric material, with two opposite parts or segments 26 and 27 clamped together about the cable, as by means of bolts 28, 28. The segments have mating cavity portions 29, 29 providing a cavity 30, opening at opposite ends of the casing, in which is mounted a normally open switch 31. This switch may include a metal clip 32, secured to the casing, on which is a fixed contact point 33, and a metal clip 34, also secured to the casing, from which extends an elongated springy contact element 35 having its free end portion normally closely spaced from the fixed contact point 33. The cable 23 extends through the cavity 30, as shown in Figure 3, one wire 37 thereof being continuous, while the other wire 38 is severed and bared to provide two ends which are connected to screws 39 and 40 on the metal clips 32 and 34, respectively. An elongated aperture 41 extending into the casing 24, in spaced relation to the cavity 30, is adapted to receive one or other of the handle extensions 21 of key 16 to support the key when it is not in use, as shown in Figures 2 and 4. When an extension 21 is thus received in aperture 41 a member 42 of springy material, secured at one of its ends to casing part 26, is depressed to urge a slidably mounted pin or detent 43 of dielectric material in direction whereby a rounded head 44 on the detent yieldingly presses the switch element 35 into engagement with contact point 33. As long as the key is thus properly stored the switch will remain closed and permit operation of the drill motor M.

Secured to the end of casing part 26, intermediate the mouth of aperture 41 and the corresponding opening for cable 23, is a clip 45 of springy material, providing an arcuate tang 46 terminating in a reversely bent tip end. This clip is angularly disposed so that when a key handle 21 is inserted in aperture 41 as described, the shank 15 may be swung inwardly, yieldingly past said tip end, to be firmly releasably gripped in the stored position shown in Figures 2 and 4.

In use of the apparatus described the drill 10 cannot be operated unless the key 16 is properly stored with one of its handle portions 21 inserted in the recess 41 of unit 24, as shown in Figures 2 and 4. Engagement of a handle portion 21 with springy member 42, through detent 43, holds springy element 35 in closed position against the contact point 33, thereby holding the circuit to motor M in readiness for operation of the drill,

2

as by manually operating a suitable switch S mounted in the drill. Because the drill cannot be operated unless the key is so positioned, the key is always readily available for adjusting the chuck 11 for inserting or removing the drill 12, and the adjustment cannot be made while the motor M is running, because removal of the key from the unit 24 opens the circuit to the same, as best shown in Figures 3 and 6.

Modifications of the invention may be resorted to without departing from the spirit thereof or the scope of the appended claims. As an example, the safety key-holder unit 24 may be mounted on a fixed structural part of a drill press or similar machine tool.

What is claimed is:

1. A safety switch as for use with a power tool requiring a separate chuck-locking key having an elongated projection thereon, comprising a relatively fixed casing having a recess for slidably receiving a substantial length of said key projection therein to support the key on the casing, switch contacts in said casing adapted to be in electrical connection to a said power tool, said switch contacts when open preventing operation of the power tool, and switch actuating means in said casing including a portion yieldingly engageable by said key projection upon reception thereof in said recess to close said switch contacts and thereby permit operation of the power tool.

2. A safety switch as for use with a power tool requiring a separate chuck-locking key having an elongated projection thereon, comprising a relatively fixed casing having a recess for slidably receiving a substantial length of said key projection therein to support the key on the casing, switch contacts in said casing adapted to be in electrical connection to a said power tool, said switch contacts when open preventing operation of the power tool, and actuating means in said casing operable by reception of said key projection in said recess to close said switch contacts and thereby permit operation of the power tool, said switch contacts including a contact element yieldingly movable between opened and closed positions, said actuating means including an actuating an elongated resilient member extending lengthwise within said recess and yieldingly compressible by said key projection upon reception thereof in said recess, and interengaging portions between said contact element and said actuating member, whereby depression of the actuating member is effective yieldingly to urge the contact element to said closed position.

3. A safety switch as for use with a power tool requiring a separate chuck-locking key having an elongated projection thereon, comprising a relatively fixed switch casing having a recess for longitudinally slidably receiving a substantial length of said key projection therein to support the key, switch contacts in said casing adapted to be in electrical connection to a said power tool, said switch when open preventing operation of

the power means, and resilient switch actuating means in said switch casing including means extending into said recess and engageable by said key projection upon reception thereof in said recess to close said switch and thereby permit operation of the power means, means being provided on said switch casing for releasably retaining said key in said switch closed position thereof.

4. A safety switch as for use with a power tool requiring a separate chuck-locking key having an elongated projection thereon, comprising a relatively fixed casing having a recess for slidably receiving a substantial length of said key projection thereon to support the key on the casing, switch contacts in said casing adapted to be in electrical connection to a said power tool, said switch contacts when open preventing operation of the power tool, and switch actuating means in said casing including a portion yieldingly engageable by said key projection upon reception in said recess to close said switch contacts and thereby permit operation of the power tool, said electrical connection including an insulated electrical cable having wire connections to said switch contacts at a point remote from said power tool, said casing being segmental and having securing means for clamping the segments together to support the casing on the cable.

5. A safety switch as for use with a power tool requiring a separate chuck-locking key having an elongated projection thereon, comprising a relatively fixed casing having a recess for longitudinally slidably receiving a substantial length of said key projection therein to support the key on the casing, switch contact means in said casing having electrical connection to a said power tool, said switch contact means when open preventing operation of the power tool, and switch actuating means in said casing including resilient means extending into said recess and yieldingly engageable by said key projection upon reception thereof in said recess to close said switch contact means and thereby permit operation of the power tool, said electrical connection including an insulated electrical cable having wire connections to said switch contact means to be at a point remote from said power tool, said casing comprising opposite segments defining said aperture and a hollow portion containing said switch contact means, and securing means being provided for clamping said segments together to support the casing on the cable.
